METHOD AND DEVICE FOR MECHANICALLY
ATTACHING PINS TO FLY CATCHER
TAPESFriedrich Kaiser, Waiblingen, Wurtemberg,
GermanyApplication September 21, 1932, Serial No. 634,255
In Germany December 18, 1931

11 Claims. (Cl. 153—10)

This invention relates to a method and device for mechanically attaching a suspension pin to the looped draw tape of fly catchers of the adhesive band type, particularly a drawing pin whose head is fitted with a projecting finger adapted to form an eye for holding the looped draw tape.

Drawing pins were hitherto secured to these tapes by hand or primitive means either by running the tape through an opening in the head of the pin or by clamping it in position by means of a projection on the pin head. Hand work, however, is expensive and requires much time, and if the drawing pins are attached during one of the first operations they will be very troublesome during subsequent operations. These drawbacks are eliminated by the method and device according to the invention.

The new method consists in mechanically picking up the drawing pins kept in a container one by one or in small numbers, placing them on a moving support, the motion of which arranges them on their backs, i. e., the top sides of their flat heads, sorting them, conveying them individually on another moving support, and positively orienting them on this support so as to place the fingers serving for forming the eyes for holding the looped tape in a certain direction and facilitate thereby the attachment thereto of the tape members of the finished fly catchers, whereupon the fingers are bent down and thus caused to form an eye. All these steps are successively and automatically carried out in the device according to the invention, which constitutes a self-contained unit and comprises a feed plunger for lifting the drawing pins supplied haphazardly to a container individually or in small numbers out of the latter and onto a shaking trough, one or several sorting-wheels insuring the continuous supply of pins to a rotary table, and the rotary table just mentioned which is fitted with holding means. On this table the drawing pins are oriented by a special device preparatory to attaching the tape member to the finger projecting from the pin heads and bending the finger into a closed eye by means of a clamping plunger.

By way of example, the device according to the invention is illustrated in the accompanying drawings, in which Figure 1 is a side view thereof, showing particularly the container for the drawing pins, the sorting-device, and the rotary table for the oriented pins; Fig. 2 is a side view, partly in section, of the means for feeding drawing pins to the rotary table, of the holding means and the device for bending and closing the fingers

of the pins; Fig. 3 is a top view of the device in its entirety; Fig. 4, a side view of the device for orienting the pins; Figs. 5 and 6 are detail views showing the shape of the drawing pin and how it is attached to the fly catcher; Fig. 7 is an enlarged fragmentary detail of the rotating table and the reciprocating slide for moving the pins thereto.

Referring to the drawings, 1 is the container for the drawing pins arranged therein without regard for order. 2 is a plunger having a flat or slightly recessed top and being capable of moving up and down in the container 1. An arm 43 is engaged with the plunger 2 and being pivotally mounted at 43 is engaged by a cam 44 on a shaft 45. During the rotation of the shaft 45 the arm 43 together with the plunger are actuated. The plunger 2 lifts at each upward stroke one or several pins out of the container 1, which by means of the stripper 3 oscillating transversely to the plunger 2 are conveyed through the chute 4 into the shaking trough 5 which is obliquely disposed both in longitudinal and transverse direction and, by suitable means, is intermittently shaken in longitudinal direction. 70 Rotary movement is imparted to the stripper from the shaft 45 through gear wheels 46 and an upright shaft 47. Owing to this shaking motion, the drawing pins passing down the trough 5 are placed on their backs, so that the fingers *a* to which the tape members are to be fastened are pointing upwardly. Shortly before reaching the lowest corner of the trough, the pins pass through a lateral opening 6 and over an inclined plane 7 into the sorting device. A 80 second opening 6a provided in the lower cross wall of the trough 5 permits pins that have failed to pass out through the opening 6 to drop into a collector 8.

The sorting device comprises several obliquely arranged sorting wheels which slowly rotate by any well known means. The sorting wheel 9 has on its circumference uniformly spaced notches for successively and singly receiving the drawing pins coming out of the shaking trough 5 and passing towards the circumference of the wheel on the inclined plane 7, the pins being further conveyed by the guide rail 11 which curves around the lowest wheel portion and prevents the pins from dropping out. Pins that fail to be accommodated by the notches 10 drop back again into the collector 8. Preferably, in addition to the sorting wheel 9, there are mounted on the inclined plane 7 and below the wheel 9 one or several sorting wheels 12, 13 which, progressively, 100 105 110

rotate more slowly than the wheel 9. This will result in an accumulation of pins in front of the second and third wheel, so that in the second or surely in the third wheel all the recesses will be provided with pins.

On leaving the last sorting wheel 13, the pins slide over the inclined plane 7 into a groove 14 which catches them successively and which contains a reciprocating slide 15 moved forward by a cam 16 and a lever 17 with the slide roll 18, and withdrawn again by a spring 19. The feeding of the pins is so timed that one is supplied to the groove 14 just before each stroke of the slide 15. The slide 15 is chamfered in front and, during its advance, moves the pins arriving in the groove ahead of it one after another onto the rotary table 20 which passes it on the same level, is moved in a step by step manner and serves for facilitating the attachment of the tape member *b* to the pins as will be hereinafter described. The table 20 is provided at the edge of its surface with equidistant hollows 21 for the reception of the drawing pins which during the advance of the slide 15 are successively arranged in steps. The front beveled surface of the slide 15 bears against both the prong and finger of the pin *a* so that as the drawing pin is moved the prong and finger thereof is always disposed in a predetermined position as illustrated in Fig. 7.

In order to cause the pins to point with their fingers towards that portion of the circumference of the table 20 where the draw or pull tape is to be attached to the finger of each pin, a bolt 22 capable of rotating always in the same direction about an axis parallel to that of the table is provided which successively moves down over each hollow 21, carries out a complete revolution and, by means of a downwardly extending eccentric tappet 23 which sooner or later will contact with the pin fingers, turns the pins into the proper position required for attaching the pull tapes.

On a horizontal driving shaft 24 always rotating in the same direction a helical gear 25 is disposed which meshes with the wheel 26 bearing a toothed rim 27 the teeth of which are engaged by the two opposite teeth 28 of a driver firmly connected with the bolt 22 guided in the wheel 26 so as to be rotatable and liftable. The driver has an annular groove which is engaged by two bolts 29 on a forked lever 30 which can rotate about a horizontal shaft 31 and can be alternately moved up and down by a cam 32 on the shaft 24. During its descent, the teeth 28 of the driver will rest on the teeth 27, so that the driver and the bolt 22 will be rotated to the extent of one complete revolution which will come to an end when a nose 33 secured to the driver strikes the lever 34. At this moment, the cam 32 starts the re-ascent of the forked lever 30 together with the driver 28 and the bolt 22. The lever 34 is rotatable about a vertical shaft and is controlled by a cam 35 on the shaft 24 so as to release the nose 33 at the proper time. The motion of the rotary table 20 is effected in known manner, as for instance, from a shaft 40^a through an intermeshing drive gear 41 of suitable form.

On the surface of the rotary table 20 are positively guided or cushioned slides 37 which correspond in number to that of the hollows 21, reciprocate radially and are controlled by a cam 36, the said slides, on moving out, partly covering and holding in position the drawing pins disposed in the hollows 21, and during this time the looped pull tape may be attached to the finger *a* from a circumferential point of the table indicated at

y in Fig. 3 within holding range by an operator or automatically. To depress the finger *a*, a plunger 39 alternately moved up and down by means of the cam 38 and a spring 38^a is provided at another suitable point of the circumference of the table 20, which during its descent acts with its pressure pin 40 on the finger *a* projecting obliquely in upward direction from the head of the drawing pin, and presses it down over the pull tape. The depression takes place preferably in two steps by means of two plungers 39 arranged one behind the other on the circumference of the table 20, the first plunger acting merely on the free ends of the finger *a* and depressing the fingers so as to bend them while the second plunger acts on the center of the finger *a* and presses it down so that it forms with the pin head an eye adapted to receive the pull tape without clamping it, whereby it might be subjected to damage.

I claim:—

1. A method of mechanically attaching a suspension drawing pin to the adhesive band of fly catchers by means of a looped pull tape, particularly for attaching a drawing pin having a projecting finger on the pin side of its head, which consists in picking up the unarranged pins from a container, sorting the pins, placing the pins individually with their pin portions and fingers pointing upwardly on a suitable support, 105 orienting the pins, holding the oriented pins in position while attaching the looped pull tape to the finger and bending the finger upon the underside of the pin head to form an eye.

2. A machine of the character described, comprising a receiver for unarranged drawing pins, a shaking trough, means for removing the pins from the container and conveying them to the trough, the said trough shaking the pins fed to it so as to place them on their heads with the 110 pin portion pointing upwardly, an outlet in the said trough for the pins, sorting means adjacent to the outlet to receive the pins coming on their backs out of the outlet and conveying them individually and equidistantly, conveyor means for 120 the pins, a movable device opposite the said conveyor means for orienting the pins on the said conveyor means, means for holding the pins in position while they are placed on said conveyor means, and means for bending down the fingers 125 of the pins.

3. A machine according to claim 2, in which the means for removing the pins from the container and conveying them to the trough comprise a plunger adapted to be moved up and down 130 in the container and accommodating a plurality of pins at its top end, and a stripper moving transversely to and fro relative to the said plunger for stripping off the pins from the top end of the said plunger at the end of each upward stroke 135 thereof and conveying them through a chute to the shaking trough.

4. A machine according to claim 2, in which the shaking trough is obliquely disposed in longitudinal and transverse directions and is intermittently moved in longitudinal direction, the outlet being provided at its lowermost corner and opening into the sorting means, and in which another outlet is disposed in the lower cross wall for the pins failing to pass out through the first 145 outlet.

5. A machine according to claim 2, in which the sorting means comprise an inclined plane, a plurality of sorting wheels arranged one behind another on the said inclined plane and rotating at 150

decreasing speeds in the same direction, a plurality of equidistant circumferential notches on the said wheels for the reception of the pins coming out of the shaking trough, and a guide rail embracing the lowest portion of each wheel for catching and conveying the pins.

6. A machine of the character described, comprising a receiver for unarranged drawing pins, a shaking trough, means for removing the pins from the container and conveying them to the trough, the said trough shaking the pins fed to it so as to place them on their heads with the pointed member extending upwardly, an outlet in the trough for the pins, an inclined plane adjacent to the outlet, a plurality of sorting wheels arranged one behind the other on the said inclined plane and rotating at decreasing speeds in the same direction, a plurality of equally spaced circumferential notches on the said wheels for receiving the pins coming out of the shaking trough, a guide rail embracing the lowest portion of each wheel for catching and conveying the pins, a catch groove below the last sorting wheel, a rotary table passing the said groove at one end thereof on the same level and moving stepwise with the last sorting wheel, a plurality of circular hollows in the rotary table for receiving pins, and a reciprocating slide in the said groove at the end thereof opposite the rotary table, the said slide being controlled relative to the last sorting wheel and the rotary table to supply at each motion in the direction of the table one hollow thereof with a pin.

7. A machine according to claim 6, in which a bolt capable of rotating always in the same direction about an axis parallel to that of the rotary table is provided above the table and at the edge thereof and adapted to be lowered over each hollow of the table and to make a complete revolution and in which the said bolt has a downwardly extending eccentric tappet adapted to come into contact with the fingers of the pins and to turn the fingers into proper position for attaching the pull tapes.

8. A machine according to claim 6, in which radially movable slides corresponding in number to that of the hollows are provided on the surface of the rotary table and, further, means for controlling the said slides adapted to cover partially the pins lying in the hollows and temporarily holding them in position.

9. A machine according to claim 6, in which a plunger adapted to move up and down is provided on the edge of the rotary table to depress the fingers of the pins.

10. A machine according to claim 6, in which two plungers adapted to be moved up and down are provided on the edge of the table, one of the said plungers acting on the ends of the fingers of the pins located at one point of the rotary table and the other plunger acting on the finger of the pin located at another point on said table.

11. A machine according to claim 6, in which all parts are arranged on a common base plate.
